METHOD AND APPARATUS FOR CONTINUOUSLY ELECTROPLATING HEAVY WIRE AND SIMILAR STRIP MATERIAL

Herbert Kenmore and Walter J. Manson, New York, N. Y., assignors to Kenmore Metal Corporation, New York, N. Y., a corporation of Delaware

Application September 14, 1950, Serial No. 184,884

11 Claims. (Cl. 204—28)

1
This invention relates to a new process and apparatus for treating rigid metal rod material, such as heavy wire or strips, in various liquid treating baths. More specifically, the invention relates to an apparatus and process for coiling heavy metallic wire and similar strip material and continuously passing it in the form of a helix through a series of baths including an electroplating bath.

The coating of wire by the hot dipping method or by electroplating heretofore has always been done by the passing of wire through a series of tanks in straight line for treatment and coating. These tanks are arranged linearly and are of a length such as to provide for the necessary period of contact between the wire and the treating baths. The faster the wire is to move or the heavier the coating, the longer each individual tank has to be. The wire itself has to be flexible enough to be bent over the walls of the tanks from one operation into the other.

Where heavy deposits are needed, the time for the wire to stay in one tank is such that tanks sometimes 300 to 400 feet long have to be constructed. Some tinning or galvanized installations necessitate a working space which is 400 to 800 feet long. In order to increase production, a multitude of strands are fed through the equipment. This type of operation does not produce a wire with a concentric coating and limits the choice of the base wire or coating. In the first place, only soft and very pliable base material can be used and the wire has to be in very fine sizes. In the second place, the amount of coating is very restricted because heavy coatings would necessitate impractical tank sizes. It has been repeatedly suggested to do away with these disadvantages by moving a helix through a series of treatment baths and thus reduce the working space to a considerable extent. Many attempts have been made to improve such operations, but none of the improvements have been entirely successful in overcoming all the difficulties accompanying this type of plating process.

The prior disclosures have the following two characteristics in common:

1. The disclosed apparatus requires that the process be a batch or discontinuous one (at least the work always has to be stopped in order to allow time to weld the beginning of one wire coil to the end of another wire coil).

2. The material plated always must be soft and this requires that the operation of the machine be extremely slow. The present invention avoids these two limitations and in so doing gains some

very distinct advantages as will be seen in the disclosure below.

In application No. 534,543 filed May 8, 1944, now Patent No. 2,495,695, an apparatus has also been disclosed for continuously passing a heavy wire which has been formed into the shape of a helix through a number of baths by suspending and rotating the helix between a pair of horizontally arranged, positively driven rollers and dipping the suspended portions of coils of the helix into a plurality of baths.

It is an object of the present invention to provide an improved process and apparatus whereby a heavy gauge wire can be continuously tempered, straightened, formed into a helix, having a uniform diameter and pitch (which it retains due to the temper) and passed (primarily by pushing) through a series of baths and electroplated automatically as described hereinafter in such a uniform manner as to make it possible to redraw by conventional methods such plated wire to any desired gauge as fine as any ordinary wire can be drawn.

It is a further object of the present invention to provide an improved apparatus and process whereby relatively heavy gauge and/or stiff wire can be continuously and efficiently metal plated to produce a stiff finished product at very high speeds of over 90 feet per minute.

It is a further object of the present invention to provide an apparatus and process whereby a stiff, tempered wire may be formed into a helix and run at high speed through a series of treatments.

It is a further object of the present invention to provide an improved process and apparatus for electroplating metal bodies such as relatively heavy wire or strip material continuously and in such a way as to prevent excessive oxidation during the process and thereby produce a bond between the base material and the plating of such adhesiveness as to permit redrawing without flaking, cracking or other deterioration of the coating.

Another object of the invention is to provide an apparatus having a means for forming a stiff tempered wire into the form of a helix having a uniform coil size and a uniform pitch and for simultaneously pushing the wire to rotate the formed helix and cause it to move along a horizontally arranged supporting means adapted to hold a large number of coils and to rotate with the helix as it is formed, in combination with a plurality of baths so constructed as to surround the major portion of each of the supported helix

coils and yet to eliminate any contact between the wire and the walls of the baths.

These objects and others ancillary thereto are accomplished by providing an apparatus which carries out the following process steps: first, straightening and, if necessary, additionally tempering the wire; second, continuously curving the straight, tempered wire into the form of a helix having a uniform coil size and a uniform pitch; third, passing the so formed helix (primarily by pushing the straight portion of the wire) to a horizontally arranged, rotating, supporting roll which roll is of considerably less diameter than the diameter of the helix but which has a peripheral speed equal to that of the wire in the helix; fourth, dipping the major part of each of the suspended coils of the helix into a plurality of baths including cleaning and electroplating baths which baths are held by a series of abutting containers so constructed as to avoid any frictional contact between the walls of the containers and the wire of the helix passing through the liquids in the containers. The path that the wire being treated travels outside of the baths must be limited to prevent oxidation and in no part of the path from the cleaning bath to the end of the electroplating bath is a complete coil of the helix subjected to the oxidizing influence of the atmosphere. In other words when a given point on the helix passes out of one bath it then passes over the supporting roller and directly into the next bath.

The apparatus and process of the invention is applicable to any type of metal strip material which is bendable to coil form and at the same time of sufficient diameter and/or temper to retain the shape given it by a coil forming device. For convenience, such strip materials are referred to generally as "wire" regardless of the cross sectional shape thereof. The strip material should have a cross sectional area at least equal to that of $\frac{1}{8}$ " diameter round wire.

According to the disclosure of application No. 534,543 referred to above the sizes of the coils are maintained uniform in passing through the baths by pressing a top roller against the wire on the supporting roller. It has now been found possible to omit the top roller by providing properly tempered wire, by preventing frictional engagement between the wire and the bath walls and by forming the helix with a predetermined uniform pitch as well as with a uniform coil diameter. However, it is sometimes advantageous to add the top roller to improve the stability of the device. Whether the top roller is employed or not the main force which moves the helix through the baths according to the present invention appears to be the combination forces furnished by the bottom roller and the pulling or pushing force provided by the two or more rotated gripping rollers which grip and forward the wire back of the helix forming device. A set of straightening rollers is located adjacent to the rotated gripping rollers and a helix forming device follows the said gripping rollers. The helix forming device may consist of a single grooved roller which is offset from the common tangent of the gripping rollers and from the straightening rollers in such a manner as to impart both a definite curvature and a definite pitch to the wire which is forced to bend by the said roller. The roller type of straightening device may be placed between the gripping rollers and the offset roller or may precede the offset roller. At least one of the pair of gripping rollers is positively driven so as to impart a tan-

gential push which is not only sufficient to force the wire over the helix forming roller but is also sufficient, in cooperation with the rotating helix supporting roller, to cause the entire helix being passed through the apparatus to rotate.

In contrast to the general belief and quite unexpectedly, it has now been found that one basic and essential feature of the invention consists in transforming the wire into a firm, rigid body. 10 This body can be visualized, for example, as a huge spiral having approximately 120 individual coils or contours 30" wide and a total 15' long. The pitch and the distances between any two adjacent coils are equal and predetermined. This firm body has to be continuously formed as it is treated. This firm body moves, as such, through the treating tanks and there can be no friction to the individual coils or contours when leaving one treatment tank and entering the next. If 20 friction were present, the firm body would lose its shape and rigidity and could not move through the apparatus any more.

It is, therefore, essential that a substantially uniform temper be incorporated into the strip material or wire before this firm body of spirals or multiples of spirals is formed. In rare cases, 25 the wire may have sufficient temper already, but is usually desirable to impart an additional temper to the wire or other strip material just before forming it into the helix. This additional temper may be given to the wire by pulling it through a reducing die located adjacent the coil forming mechanism. The reducing die in addition to adding temper to the wire serves to remove small kinks, scale and rust and in general, provides a smooth, stiff wire.

The wire may be pulled away from the original commercial coil in an axial direction so that the original coil may be held in a stationary position and so that the free end of the coil may be welded to the end of the next coil to be treated. In this way it is never necessary to stop the operation of the machine because the end of a coil of wire is reached. On the other hand, if it does become necessary or desirable to shut down the machine, the wire starting into the baths may be cut at any time without wasting either time or wire. When cut, the wire in the machine may be passed through the remainder of the machine with the aid of a top roller and the pushing mechanism is shut down. Previously it was economically necessary to complete the plating of any coil of wire which had been partially introduced into the apparatus, and consequently, when the apparatus was started again, it was necessary to thread up the entire machine.

The novel features characteristic of this invention are set forth with particularity in the appended claims. The invention itself, however, both as to its organization and its method of operation, together with additional objects and advantages thereof, will best be understood from the following description of specific embodiments when read in connection with the accompanying drawings, in which:

Figure 1 is a perspective view of the apparatus of the present invention.

Figure 2 is a top plan view of the apparatus, partly cut away.

Figure 3 is a cross-sectional view through an electroplating tank along line 3-3 of Figure 2.

Figure 4 is an end view of the apparatus.

Figure 5 is a cross-sectional side view taken along line 5-5 of Figure 2.

Figure 6 is a detail view showing how the

curvature and pitch of the helix is imparted to the straightened wire.

Figure 7 is a side view of the stiff, spring-like coil.

Figure 8 is a top plan view of a modified form of bath construction.

The preliminary treatment of the wire to be sure it has the proper temper and stiffness to retain a helical shape and to change it to the required helical shape in which the coils have a uniform pitch and diameter before pushing and/or forwarding the helix through the liquid treating part of the apparatus is very important. As indicated in Figure 1 wire 10 from the coiled bundle 11, which bundle 11 is preferably held non-rotatably on the stand 20, is drawn off the coil 11 more or less axially. Drawing the wire 10 off the coil axially gives it a 360° twist per coil but this does not interfere with the process when the subsequent treatments set forth below are included and by holding the bundle 11 stationary on the stand 20 it is possible to weld the free end 12 thereof to the end 12 of another bundle 11' held on stand 21 while the wire 10 from bundle 11 is passing through the apparatus. The wire 10 is pulled off the bundle 11 by the drum 30 and is passed through the die 31 between the bundle 11 and the drum 30. The die 31 is small enough to reduce the diameter of the wire slightly and to remove scale and irregularities but it also has a beneficial effect in increasing the temper of the wire to make the wire stiffer and capable of retaining the curvature and pitch to be imparted thereto. The wire is drawn from the drum 30 by the pair of gripping and forwarding or pushing rollers 32, 33 and is then passed through the straightening device 40, 41 and to the coil reforming roller 50 which imparts a definite uniform curvature and a definite uniform pitch to the wire forced over it. The roller 50 is spaced from rollers 46, 48; as shown in Figure 6, both tangentially and axially so as to impart a pitch as well as a curvature to the wire 10. From the coil reforming roller 50 the coiled wire passes to the horizontal helix supporting roller 60. Preferably several coils of the helix thus formed rotate outside of the treating bath section of the device and the coils then pass into the first of the series of baths. When the machine is to be closed down the wire can be cut somewhere between that portion which is just about to enter the bath and the first complete coil following the roller 50 and the remainder of the wire in the bath is passed on through and completely treated.

The gripping rollers 32, 33 which push the wire through the apparatus are driven from the shaft 34, gear 35, chain drive 36, and shaft 37. The shaft 61 which is attached to the forwarding roller 60 is driven by gear 62, chain 63, shaft 64 etc. The shafts 37 and 61 are driven from a common source of power if desired, but the gear boxes 38 and 65, shown diagrammatically, include adjustable speed change devices (adjusting means not shown) such as a Reeves drive.

In operation the speeds of these two shafts 34 and 61 must be synchronized to maintain proper coil size and machine operation.

To illustrate: If the speed of shaft 34 is faster than the speed of 61, the diameter of the coils 10' immediately following the coil forming roll 50 will become larger and this enlarged diameter will gradually work its way into the plating tanks and will eventually tangle with the outside anodes 126, 127 (see Fig. 3).

If the speed of shaft 34 is slower than the speed of shaft 61, the reverse will happen: The coil size following the coil forming roll will become smaller and this small diameter coil will eventually tangle with the inside anodes 134 and 135.

It has been learned by experience that the coil diameter should not vary more than plus or minus one inch from that originally set by the coil forming roll 50. To accomplish this requires continual manual or automatic speed regulation of one or the other driving parts 38 or 65.

The speed of the devices cannot be fixed apparently because the various characteristics of the wire such as temper, uniformity of diameter, etc. are continuously changing, making it impossible to perfectly match the peripheral speed of the drawing rolls 32, 33 and the bottom roller 60.

The two units 40 and 41 of the straightening device are positioned at approximately right angles to each other. The first unit 40 comprises a plurality of pulleys 42, 42 mounted on vertical shafts 43 at one side of the unit and an equal number of pulleys 44, 44 mounted on shafts 45 at the opposite side of the unit and positioned so that the wire is contacted alternately by a pulley 42 and a pulley 44 as it passes through the unit 40. Similarly the pulleys 46 in shafts 47 are mounted at the upper side of unit 41 and the pulleys 48 in shafts 49 are mounted on the lower side of the unit 41.

As the wire 10 is pushed past the straightening unit 41 it is curved by the roller or pulley 50, the peripheral groove 51 of the pulley 50 being spaced vertically from the wire contacting grooves of the pulleys 46 and 48 of straightener unit 41 to impart a definite uniform curvature to the straightened wire. The plane of rotation of the pulley 50 is substantially parallel to but spaced horizontally from the plane of rotation of the pulleys 48 so as to give the helix 10' which is formed a definite uniform pitch. The shaft 54 is rotatably mounted in a block 52 which contains suitable adjusting means 53 for varying the distance of the pulley 51 from the block 52.

As shown in the drawing the straightening device 40, 41 and the recoiling means 50 are located tangentially with respect to the lower part of the helix which is formed. These devices, however, can be located tangentially to the helix 10' which is formed, at any point about the circumference thereof.

The roll 60 extends horizontally above a number of separate, adjacent, bath chambers 70-78. The series of baths 70-78 are adjacent one another so that from the time a given point on the helix 10' is immersed in the first bath it never travels in the air at one time for a period as long as the time it takes for the helix 10' to rotate once and/or it is never allowed access to the air for a period of over 20 seconds at one time. This limitation on the time of contact with the air between the cleaning and electroplating baths and between each emersion and the next subsequent immersion in the electroplating bath is absolutely essential. It would be possible to permit one or more turns to travel in air between a degreasing bath and the cleaning bath, for example, although it is preferred to have all the baths abut one another for the sake of compactness and rigidity of the apparatus.

So that the position of the helix 10' which is passing through the treating baths shall not be slowed up by friction or contact with the walls

of the baths a particular and unusual type of end wall and separating partition has been devised. That is, the upper part of the wall is sloped in one direction (the axial direction of the approaching wire) at one side thereof and is sloped in the opposite directions on the other side. The sloping portions start from a horizontal line which is located approximately at the center portion or axis of the helix 10'. A very satisfactory structure is shown at the end wall 80 of the bath 70. Below the horizontal line 81 the end 80 is substantially straight and is attached at right angles to the sidewalls and bottom of the bath structure. From the line 80 upwardly the right side 82 of the end 80 slopes inwardly with respect to the bath 70 and from the line 80 upwardly the left hand side 83 slopes outwardly so that that portion of the helix designated as A which is just passing into the bath 70 does not contact any part of the bath end wall 80 even though the wire passes over the roller 60 at an angle of approximately 90°. The sloping portions 82 and 83 are connected by the triangular portion 84 which extends down from the central portion of the partition. So that the edges of the end wall or the partitions can be connected rectilinearly to the tank, the sloping areas 82 and 83 are shown as ending adjacent to but slightly spaced from the sides of the tank. The sloping areas extend beyond the space which is traversed by the helix and the side edge 85 of the wall 80, for example, lies in the same plane as that portion of the wall below the line 81. This side edge 85 is connected to the slope portion 83 by a triangular portion 86 (only partly shown) which is approximately equal to a bisected portion of the triangular section 84. The drawing shows sharp right angle turns or bends connecting the sloping portions 82 and 83 to the center connecting portion 84 and the side triangular portion 86 but it is obvious that these bends may be considerably rounded off, if desired, since the helix does not approach closely to the extreme side portions or the center part of the partitions or walls 80. The side parts 85 and 86 can be omitted altogether since the only disadvantage of such omission is to make it slightly more difficult to align the partitions when building the apparatus. As best shown in Figure 2 the side walls 90, 91 of the tank 71 may be united to the side walls 92, 93 of an adjacent tank 72 by means of the laterally extending flanges 94, 95, 96 and 97. The edges 85' of the partition 80 being held between two adjacent flanges 96 and 97. Some of the partitions may be attached to the edges of the side walls as shown at 89'. The end walls 80 as shown extend above the level of the roller 60 and have a slot 88 (see Figures 1, 3 and 4) which extends further away from one side of the roller 60 than from the other.

The remaining partitions or end walls are constructed similarly with the two sloping sides 82 and 83, etc., so that in its complete path of travel through the baths, the wire never comes into contact with the walls thereof. When operating at high speeds of over 50 feet per minute, for example, this freedom from frictional engagement with the bath walls is of tremendous importance since at such speeds merely momentary contact with the bath walls frictionally holds back the particular coil which makes the contact sufficiently to change its diameter and once the diameter of a coil at a particular part of the apparatus is changed every subsequent

portion of the wire which passes that part will be given approximately the same reduced or increased diameter. The condition is likely to be aggravated more than alleviated by continuing the operation of the apparatus after one portion of the helix has been distorted. Every time one coil of the traveling helix is decreased in circumference another adjacent coil is increased in circumference by an equal amount. For example, variations of plus or minus one inch in diameter in the coils of a helix which is 36 inches in diameter result in a non-uniform plating. One may qualitatively estimate the cumulative result due to continued frictional contact from the fact that a forwarding roller 60 which has a diameter of about 6" and in which the diameter varies from end to end by $\frac{1}{16}$ " does not work satisfactorily due to the variation in coil size which it gradually builds up.

20 A top roller 100 may be pressed against that portion of each coil which contacts the top of the forwarding roller 60. The roller 100 is rotatably supported in the bearing plates 101 and 102 which in turn are held by the overhanging frame structures 103 and 104 located at the ends of the apparatus. Suitable adjusting means 105 and 106 are provided to adjust the distance between the top roller 100 and the roller 60 so that wires of different diameters can be processed. 25 This top roller 100 may be omitted in the apparatus of this invention especially when the wire is tempered and when there is no frictional engagement with the walls of the tank.

30 The sequence of baths employed depends somewhat upon the metal being plated but it should always include at least one cleaning bath before the electroplating bath. In the apparatus shown the following sequence of baths may be employed. Bath 70 may be an electrolytic cleaning bath containing an aqueous solution of sodium phosphate. In this bath the wire is made the anode by means of the electrical contacts 110 held on the bar 111. Cathodes are shown at 112 and 113. From the bath 70 the wire passes to bath 71 which contains a cold water rinse. Suitable means such as tap 113 may be associated with this bath to continuously replenish the water therein. The next bath 72 may be a hot sulphuric acid bath which is followed by a cold water rinse bath 73. Bath 74 is another electrolytic cleaning bath containing electrode contacts 114 for the wire and electrode connecting bars 115 and 116 for the bath. The bath 76 may be a polarizing or a flash plating bath and has an electrode contact 117, etc.

35 40 45 50 55 60 65 70 75 80 85 90 95 100 The electroplating bath 77 shows 17 turns of the helix passing therethrough but in reality the turns are more closely spaced so that there are from 20-75 passes through the electroplating bath. The rod 111 which extends along the top of the bath adjacent the top of the helix contains a number of electrode contacts 120 and 121, one on each side of the roller 60 for each coil which is passing through the bath.

The anodes in bath are spaced about equally on both the inside and outside of the helix (see Figure 3). The outside electrodes are suspended from the anode connecting bars 122 and 123. The electrodes 124 and 125 which extend from bars 122 and 123, respectively, follow the curvature of or are substantially concentric with the wire helix 10'. The electrodes 124 and 125 may be covered with the fabric bags 126 and 127. The inner electrode supports 130, 131 hold the electrodes 132 and 133, respectively, which are also

preferably covered with the fabric bags 134 and 135. The electrodes 132, 133 are substantially equally spaced along the inside of the wire helix 10'. The pairs of electrodes 126, 127 and 134, 135 are tied together at their free ends to maintain their proper position in the bath.

The coil 10' which is formed according to the present invention is a stiff, spring-like helix in which all of the individual turns are of substantially the same diameter and pitch. That is, the diameter "d" of all the coils as shown in Figure 7 is the same and the distance "s" between any two adjacent coils is substantially the same. As long as no particular part of the helix is slowed up due to friction against a side of a bath wall the helix 10' retains the shape given it by the coil forming mechanism 50-54. The stiff helix 10' may be passed through a frictionless type of bath without the aid of the top roller as illustrated in Figure 7.

A modified form of bath construction is shown in plan view in Figure 8. In this figure the sides 190 and 191 of the first bath are parallel but slightly out of alignment so that the end sections 180 connect to the side walls at an angle which is slightly different from a right angle. The end walls 180 may be secured to the side walls in the same way that the end walls 80 of Figures 1 and 2 are connected to the side walls 90 and 91, for example, by means of flanged sections 191 and 196 of the side walls 190 and 192 respectively, and the extending edge 185 of the end walls 180. Additional end or cross walls 180' may be added as shown in Figure 8. Although Figure 7 is a side elevation and Figure 8 is a plan view, the way in which the coil 10' of Figure 7 may be introduced into and passed through the bath combination of Figure 8 without rubbing against the walls 180 or 180' of the baths may be visualized by imagining that the helix of Figure 7 is lowered into the baths of Figure 8. It can be seen that the walls 180 or 180' will substantially bisect the space between two adjacent individual coils or turns of the helix.

It is readily understood that by combining a wire straightening and coiling means with the electroplating apparatus any kind of wire which has the proper stiffness or is of sufficient size to be made stiff by tempering can be plated in such a way as to produce a plated product which can be drawn to any desired final size. With the apparatus of this invention heavy wires which may be rusted, scaley and crinkled, in short or long lengths, and with various degrees of temper, can be plated.

This application is a continuation-in-part of application Serial No. 732,812, filed March 6, 1947, now abandoned.

We claim:

1. In the method of plating wire having a cross sectional area at least equivalent to that of a round wire of .75 mils diameter to continuously produce a plated wire which is capable of being drawn after plating without rupturing or removing the plate, the steps comprising providing a wire having a large cross sectional area equivalent to at least that of a round wire of .75 mils diameter with a work hardened surface sufficient to cause the wire to retain the linear shape which is forcefully imparted thereto, applying a propelling force to said wire to move a strand of the wire axially in a straight direction, subjecting the propelled strand of wire to a plurality of linearly arranged opposed forces perpendicular to the axis of said wire to straighten the same, immediately

thereafter curving the propelled strand of wire in a direction which is in a generally vertical direction but inclined slightly from the true vertical so as to form the wire into a helix of uniform size and pitch, the energy for straightening and curving said strand of wire being applied by said propelling force, continuously supporting and applying a rotating force to a large number of adjacent coils of said helix as they are formed so as to feed said helix along a helical path having a horizontal axis, synchronizing the said rotating force applied to said coils of said helix with said propelling force so as to prevent the development of frictional forces between the helix and the means through which said rotating force is applied to said helix, treating the suspended portions of said supported coils with a continuous series of liquid treating baths including a cleaning bath and an electroplating bath, the said propelling and rotating forces having such a speed that no substantial oxidation of the wire takes place from the time the wire of the helix enters the cleaning bath until it leaves the electroplating bath.

2. In the method of plating wire having a cross sectional area of at least equivalent to that of a round wire of .75 mils diameter to continuously produce a plated wire which is capable of being drawn after plating without rupturing or removing the plate, the steps comprising providing a wire having a large cross sectional area equivalent to at least that of a round wire of .75 mils diameter, work hardening said wire strand by drawing it through a die, applying a propelling force to said work hardened wire strand to push the wire axially in a first direction, subjecting the propelled strand of wire to a plurality of linearly arranged, opposed forces perpendicular to the axis of said strand of wire and extending in said first direction to continuously straighten said strand, immediately thereafter continuously curving said wire into the form of a helix about a horizontal axis perpendicular to the plane of said first direction by continuously applying a curving force which is out of alignment with both the perpendicular and the horizontal planes of said first direction, the energy for propelling said wire axially through said opposed straightening forces and said curving force being applied by said propelling force, continuously supporting and applying a rotating force to a large number of adjacent coils of said helix as they are formed so as to continuously feed said helix along a helical path having a horizontal axis, synchronizing the said rotating force with said propelling force so as to prevent the development of frictional forces on the supported portion of said helix, treating the supported coils by passing the lower portions thereof in and out of a continuous series of liquid treating baths including a cleaning bath and an electroplating bath, the said propelling and rotating forces having such a speed that no substantial oxidation of the wire takes place during its travel outside of said baths from the time the wire of the helix enters the cleaning bath until it leaves the plating bath.

3. An apparatus for electroplating heavy gauge wire having a cross sectional area at least equivalent to that of a round wire with a diameter of .075", comprising means for holding a coiled bundle of said wire so that the wire can be unwound therefrom in an axial direction without rotating the bundle, a wire drawing die positioned to receive a wire withdrawn axially from said bundle, pulling means adjacent said die for pull-

ing the wire coming from said bundle through said die, a pair of opposed rollers adjacent said last named means adapted to grip between them the wire coming from said pulling means, means to positively rotate at least one of said gripping rollers, an elongated wire straightening means with a plurality of generally aligned wire engaging elements having one end thereof adjacent to said gripping rollers and being aligned with said gripping rollers to cooperatively coat therewith, a wire curving means comprising a curving roller adjacent the other end of said wire straightening means but out of alignment with the wire path of said wire through said straightening means and the gripping rollers so as to impart a definite curvature and pitch to the wire which is forced over the said curving roller, a rotatable elongated horizontal supporting roller having one end thereof in the region of said curving roller and extending horizontally in a vertical plane which is at substantially a right angle with respect to the path of the wire passing through said straightening means so as to cooperatively coat with said straightening and curving means for receiving said wire curved by said curving means in the form of a helix and to support a number of the individual coils of said helix in a suspended position, means to rotate said elongated supporting and suspending roller and a plurality of juxtapositioned tanks below said supporting roller adapted to surround the lower portions of consecutive coils of said helix suspended from said supporting roller, at least one electrode contact adjacent said supporting roller for carrying current to said wire and at least one electrode within one of said tanks.

4. The device as set forth in claim 3, in which said wire straightening device comprises two sets of opposed straightening rollers, a first set of said straightening rollers having their axes of rotation in a pair of substantially parallel vertical planes and the second set of rollers having their axes of rotation in a pair of substantially parallel horizontal planes, said wire curving device being located adjacent the end of said second set of straightening rolls.

5. The device as set forth in claim 3 in which said plurality of juxtapositioned tanks are separated from each other by walls the side portions of said walls being angled away from any plane perpendicular to the axis of said helix by an amount approximating the amount by which the curving device is out of alignment with the path of the wire through the straightening device.

6. An apparatus for electroplating heavy gauge wire having a cross sectional area at least equivalent to that of a round wire with a diameter of .075", comprising means for holding a coiled bundle of said wire so that a strand of wire can be unwound therefrom, a wire propelling means comprising a pair of opposed rollers adapted to grip between them the wire coming from said bundle holding means, an elongated wire straightening means with a plurality of generally aligned wire engaging elements having a first end thereof adjacent to said gripping means and being in alignment with said opposed gripping rollers so as to cooperatively coat therewith to straighten said wire, a wire curving device adjacent the other end of said straightening means but out of line with the wire path through said straightening means and the gripping rollers, means to positively rotate at least one of said gripping rollers so as to propel said wire through said straightening means and over said curving

means so as to first straighten and then to impart a definite curvature and pitch to the wire, a rotatable elongated horizontal supporting roller having one end thereof in the region of said curving roller and extending horizontally in a vertical plane which is at substantially a right angle with respect to the path of the wire passing through said straightening means so as to cooperatively coat with said straightening and curving means for receiving said wire curved by said curving means in the form of a helix and to support a number of the individual coils of said helix in a suspended position, means to rotate said elongated supporting and suspending roller and a plurality of juxtapositioned tanks below said supporting roller adapted to surround the lower portions of consecutive coils of said helix suspended from said supporting roller, at least one electrode contact adjacent said supporting roller for carrying current to said wire and at least one electrode of opposite polarity with respect to said first named electrode within one of said tanks.

7. An apparatus for electroplating heavy gauge wire having a cross sectional area at least equivalent to that of a round wire with a diameter of .075", comprising a pair of opposed rollers adapted to grip a wire therebetween, means to positively rotate at least one of said gripping rollers, an elongated wire straightening means comprising opposed sets of wire engaging rollers, one end of said wire straightening means being positioned adjacent to and cooperatively coating with said gripping rollers, said opposed sets of straightening rollers having a substantially straight opening therebetween to receive said wire as it comes from said gripping rollers and to guide said wire in a substantially straight path therethrough, said opening being substantially tangential with respect to both of the gripping rollers, a wire curving means adjacent to the other end of said straightening means but out of alignment with the path of the wire passing through said straightening means, a rotatable, elongated, horizontal supporting and suspending roller adapted to receive the wire curved by said curving means in the form of a helix and to support a number of the individual coils of said helix in suspended position, one end of said supporting roller being in the region of said curving means and the other end extending at approximately right angles with respect to the said path of said wire strand through said gripping rolls and said straightening means, means to rotate said elongated supporting and suspending roller, a change speed device connected to at least one of said means for rotating the gripping rollers and said means for rotating the horizontal supporting roller whereby the relative speeds of the two said positively rotated devices can be synchronized in accordance with the characteristics of the wire and a plurality of juxtapositioned tanks below said supporting roller adapted to surround the lower portions of consecutive coils of said helix suspended from said supporting roller, at least one electrode contact adjacent said supporting roller for carrying current to said wire and at least one electrode of opposite polarity with respect to said first named electrode within one of said tanks.

8. An apparatus for electroplating heavy gauge wire having a cross sectional area at least equivalent to that of a round wire with a diameter of .075", comprising means for holding a coiled bundle of said wire so that a wire strand can be unwound therefrom, a wire drawing die adja-

cent thereto positioned to receive the wire strand withdrawn from said bundle, pulling means adjacent said die for pulling the wire strand coming from said bundle through said die, a pair of opposed rollers adjacent to and adapted to grip between them the wire strand coming from said pulling means, an elongated wire straightening means with a plurality of generally aligned wire engaging elements in alignment with said opposed gripping rollers and having a first end thereof adjacent to said gripping rollers, a wire curving means adjacent to the second end of said elongated straightening means but out of line with the wire path through said straightening means and the gripping rollers, means to positively rotate at least one of said gripping rollers so as to propel said wire coming from said pulling means through said straightening means and over said curving means so as to first straighten said wire and then to impart a definite curvature and pitch to said wire, a rotatable, elongated, horizontal supporting and suspending roller having one end thereof in the region of said curving means and extending horizontally in a vertical plane at substantially a right angle with respect to the path of the wire passing through said gripping rollers and straightening means whereby to receive the wire curved by said curving means in the form of a helix and to support a number of the individual coils of said helix in suspended position, means for rotating the horizontal supporting roller, and a plurality of juxtaposed tanks below said supporting roller adapted to surround the lower portions of consecutive coils of said helix suspended from said supporting roller, at least one electrode contact adjacent said supporting roller for carrying current to said wire and at least one electrode of opposite polarity with respect to said first named electrode within one of said tanks.

9. An apparatus for electroplating heavy gauge wire having a cross sectional area at least equivalent to that of a round wire with a diameter of .075", comprising means for holding a coiled bundle of said wire, a wire drawing die positioned to receive the wire withdrawn from said bundle, pulling means adjacent said die for pulling wire coming from said bundle through said die, wire straightening and propelling means comprising an elongated wire straightening means with a plurality of generally aligned wire engaging elements and an associated pair of gripping rollers aligned with said wire engaging elements to cooperatively coat therewith, one end of said wire straightening and propelling means being adjacent said pulling means, a wire curving means adjacent the other end of said wire straightening and propelling means but out of alignment with the wire path through said straightening device and the gripping rollers so as to impart a definite curvature and pitch to the wire which is forced over the said curving means, a rotatable elongated horizontal supporting roller having one end thereof in the region of said curving means and extending horizontally in a vertical plane which is at substantially a right angle with respect to the path of wire passing through said straightening means so as to cooperatively coat with said straightening and curving means for receiving said wire curved by said curving means in the form of a helix and to support a number of the individual coils of said helix in a suspended position, means to rotate said elongated supporting and suspending roller and a plurality of juxtaposed tanks below said sup-

porting roller adapted to surround the lower portions of consecutive coils of said helix suspended from said supporting roller, at least one electrode contact adjacent said supporting roller for carrying current to said wire and at least one electrode within one of said tanks.

10. An apparatus for electroplating heavy gauge wire having a cross sectional area at least equivalent to that of a round wire with a diameter of .075", comprising a wire gripping and forwarding means, an elongated wire straightening means with a plurality of generally aligned wire engaging elements having one end thereof adjacent to said wire gripping means and being aligned and cooperatively coacting therewith to receive and straighten wire as it comes from said gripping and forwarding means, a wire curving means adjacent the other end of said wire straightening means adapted to cooperate with said curving means to continuously curve said straightened wire to the form of a horizontally extending helix of uniform coil side and uniform pitch, and a rotatable, elongated, horizontal supporting means having one end thereof in the region of said curving means and extending horizontally in a vertical plane which is at substantially right angles with respect to the direction of the wire passing through said wire straightening means so as to cooperatively coat with said straightening device and curving means to receive the wire as it is formed into said horizontally extending helix and to support a number of the individual coils of said helix in suspended position, and a plurality of juxtaposed tanks below said supporting roller adapted to surround the lower portions of consecutive coils of said helix suspended from said supporting roller, at least one electrode contact adjacent said supporting roller for carrying current to said wire and at least one electrode of opposite polarity with respect to said first named electrode within one of said tanks.

11. An apparatus for electroplating heavy gauge wire having a cross sectional area at least equivalent to that of a round wire with a diameter of .075", comprising means for holding a coiled bundle of said wire so that a strand of wire can be unwound therefrom, wire straightening and propelling means comprising an elongated wire straightening means with a plurality of generally aligned wire engaging elements and an associated pair of gripping rollers aligned with said wire engaging elements to cooperatively coat therewith, one end of said wire straightening and propelling means being adjacent said bundle holding means, a wire curving means adjacent the other end of said wire straightening and propelling means but out of alignment with the wire path through said straightening device and the gripping rollers so as to impart a definite curvature and pitch to the wire which is forced over the said curving means, a rotatable elongated horizontal supporting roller having one end thereof in the region of said curving means and extending horizontally in a vertical plane which is at substantially a right angle with respect to the path of wire passing through said straightening means so as to cooperatively coat with said straightening and curving means for receiving said wire curved by said curving means in the form of a helix and to support a number of the individual coils of said helix in a suspended position, means to rotate said elongated supporting and suspending roller and a plurality of juxtaposed tanks below said sup-

15

positioned tanks below said supporting roller adapted to surround the lower portions of consecutive coils of said helix suspended from said supporting roller, at least one electrode contact adjacent said supporting roller for carrying current to said wire and at least one electrode within one of said tanks.
